UNITED STATES PATENT OFFICE.

HENRY BARKMANN AND ALOIS KUTSCHA, OF CHICAGO, ILLINOIS.

AUTOTRUCK.

1,409,916.

Specification of Letters Patent. Patented Mar. 21, 1922.

Application filed April 14, 1920. Serial No. 373,696.

To all whom it may concern:

Be it known that we, HENRY BARKMANN, a citizen of the United States, and ALOIS KUTSCHA, a citizen of the Republic of Germany, both residing at Chicago, in the county of Cook and State of Illinois, have invented certain new and useful Improvements in Autotucks, of which the following is a specification.

Modern auto trucks for hauling coal and other loose material are generally constructed for discharging the load at the rear or at the side of the box body. Some trucks are provided with means for elevating the forward end of the body to tilt the body and facilitate unloading. Owing to the congested condition of many city streets and alleys, to traffic regulations, and to other conditions affecting the unloading operation it is frequently impossible to back a truck up so that the load may be discharged at the rear and hence the provision of means whereby the load may be discharged at the side when the truck is stationed alongside a street curb or in a narrow alley. But there are many times and places where it is desirable to deliver the load to a point at some distance from the truck and chutes are employed for this purpose. If the chute is comparatively long the fall will often not be sufficient to cause the coal to slide and a man must stand by and push the coal down the chute to avoid clogging and to keep the coal moving. Sometimes it is desirable to deliver the load through a chute adjusted to a substantially level plane, or even to elevate it through an upwardly inclined chute. In view of the large investment involved in auto trucks, and the employment of high priced labor for operating them, as well as to comply with traffic regulations, it is highly desirable to accomplish the unloading operation as speedily as possible so that many trips may be made daily and the obstruction of traffic reduced to a minimum. And, as before indicated, it is also desirable to provide for delivering the load at a distance from the truck to coal holes or other places more or less inaccessibly located, and without requiring any handling of the material during the unloading operation.

It is the primary object of our invention to provide an auto truck with a readily attachable conveyor and with means whereby the conveyor may be operated from the truck

motor so that the truck load may be mechanically and automatically discharged from the rear or from the side of the truck and delivered to any desired point.

The invention has other objects in view which will appear hereinafter in the detail description of the invention as embodied in a selected form in the accompanying drawings, in which—

Fig. 1 is a side elevation of a truck in discharging position with the conveyor located at the rear end thereof; 65

Fig. 2 is a detail view showing the conveyor in storage position on the side of the truck body; 70

Fig. 3 is a rear elevation of a truck in discharging position with the conveyor located at the side of the truck; 75

Fig. 4 is a detail enlarged sectional view showing the truck body in horizontal position with the conveyor attached at the rear end of the truck; 80

Fig. 5 is a longitudinal sectional view of a portion of a conveyor that may be employed; 85

Fig. 6 is a transverse sectional view of the conveyor; 90

Fig. 7 is a plan view showing as much of the truck frame as is required to understand the invention; 95

Fig. 8 is a sectional view on the line 8—8 of Fig. 7 and Fig. 9 is a sectional view on the line 9—9 of Fig. 8. 100

We have selected for illustrating the invention an auto truck in which the body or box 10 is elevated to tilted position relative to the truck frame 11 by screw devices 12 operated by the motor drive shaft 13 through the transmission 14. The motor is not shown in the drawings and the transmission is only indicated generally as they are well known in the art and may be of many different kinds. A shaft 15 is also driven from the transmission (Fig. 7) and is provided with a clutch 16 operated by lever 17. This clutch shaft carries bevel gears 18, 18' which drive a bevel gear 19 on a shaft 20 and the latter shaft drives a shaft 21 through the medium of a sprocket chain 22 (Fig. 8). The shaft 21 carries a bevel pinion 23 which meshes with a bevel gear 24 on the screw 12. The gear 18 or the gear 18' is shifted into operative engagement with gear 19 by means of lever 25 (Fig. 9) to rotate the screw forward or reverse and to raise or lower the body. 110

The mechanism thus far described forms no part of our invention and simply illustrates one form of truck operating mechanism with which the invention may be embodied.

5 The clutch shaft 15 is provided with a sprocket wheel 26 to drive a sprocket chain 27 which travels on another sprocket wheel 28 on a conveyor operating shaft 29 suitably mounted on the truck frame (Fig. 7). The 10 conveyor shaft extends lengthwise of the frame and through a sprocket chain 30 (Fig. 7) drives a side shaft 31 also mounted on the truck frame adjacent the discharge 32 at the side of the truck body near the rear 15 end thereof. A bevel gear 33 on the side shaft 32 meshes with a bevel gear 34 on the rear shaft 35 mounted on the truck frame at the rear end thereof. This shaft 35 may be provided with a belt pulley 36 so that power 20 may be taken therefrom for various purposes. The side shaft 31 may also be provided with a belt pulley if desired.

The conveyor comprises a suitable frame 37 having at each end a large roller 38 (and 25 one or more similar intermediate rollers if desired) over which an endless belt 39 travels. This belt may be provided with cleats 39' and the top lift is preferably supported upon a plurality of small rollers 40 arranged 30 close together and mounted at their ends in the sides 41 of the conveyor frame which project above the belt sufficiently to retain the material on the belt (Figs. 5, 6).

When not in use the conveyor may be suspended in storage position at the side of the body on supports 42, as shown in Fig. 2.

If the load is to be discharged at the rear end of the truck, the truck body is elevated to tilted position and the conveyor is suspended in proper relation to the rear discharge 43 by one or more chains 44 and one or more hooks 45. One end roller 38 is mounted on a shaft 38' which carries a sprocket 46 and a sprocket chain 47 is 45 trained over this sprocket and over a sprocket 48 on the rear shaft 35. Or if the load is to be discharged at the side of the truck the conveyor is similarly suspended and the sprocket chain engaged with a sprocket 50 wheel 49 on the side shaft 31. In either case the conveyor is operated from the truck motor through the mechanism heretofore described.

The rear discharge may consist of an 55 opening in the body closed by a swinging door 43. The side discharge preferably comprises a door 50 and a short chute having sides 51 and an angular bottom 52 which will be positioned horizontally to receive the 60 conveyor when the body is tilted (Fig. 1).

Our invention is simple in construction, the conveyor can be easily and quickly attached and detached, and it is operated by the truck motor by simply throwing clutch 16. This 65 conveyor insures delivery of the load to the

desired location without handling and it avoids the necessity for discharging a load upon the street or alley, as now often happens, because of the impossibility of positioning the truck close enough to a coal hole 70 or other depository. The conveyor may be arranged across a side walk and if not long enough it may discharge into an ordinary chute which will deliver the material to a more distant point. The outer end of the 75 conveyor may be elevated to deliver the material to a higher level than the discharge from the truck body. The pulley 36 may be belted to drive a loader for loading the truck.

Our invention will greatly facilitate the unloading operation and enable it to be conducted with greater speed than has been customary heretofore. The invention is especially important in connection with the delivery of coal but it may be used for many other purposes and it enables the delivery of the load in places where it cannot now be delivered direct from the truck. As before stated the operating mechanism on the 90 truck may be utilized to operate a loading machine and with the loading operation accomplished under power of the truck motor at one end of the line and the discharging operation conducted in the same way at the 95 other end of the line the work of delivering by auto truck will be greatly expedited, a greater number of trips may be made daily and a greater return on the comparatively 100 large investment necessary to acquire and maintain an auto truck will be made.

The invention has been illustrated and described herein in a selected embodiment which we have found satisfactory for the purpose but it will be appreciated that 105 changes in the construction and arrangement and proportions of parts may be made without departing from the spirit of the invention and that some changes will undoubtedly be necessitated to adapt the invention 110 for trucks of different constructions, and we therefore desire to have it understood that we reserve the right to make all such changes and adaptations as fairly fall within the scope of the following claims.

115 We claim:

1. In a device of the character described, a frame, a body supported thereon, means for tipping the body relative to the frame, outlets at a side and an end of the body, a motor, a longitudinal shaft driven by said motor, a counter shaft adjacent said side outlet, a transverse shaft adjacent to said end outlet, means for driving said counter and transverse shafts from said longitudinal shaft and conveyor adapted to be mounted adjacent either of said outlets and to be driven by the adjacent counter or transverse shaft.

120 2. In a device of the class described, a

- frame, a motor on said frame, a longitudinal shaft driven by said motor, a counter shaft driven by said longitudinal shaft, a transverse shaft driven by said counter shaft, means carried by said counter and transverse shafts adapted to transmit power to a conveyor, and means on the frame for supporting a conveyor adjacent to said counter and transverse shafts.
- 5 10 3. In a device of the class described a body having discharge outlets at a side and an end, a conveyor adapted to be mounted adjacent either outlet, a motor, a power shaft driven by said motor, and means driven by said power shaft for driving said conveyor in either position.
4. In a device of the class described, a frame, a body having a plurality of discharge outlets therein, means for tipping 20 said body to direct material therein to said outlets, a motor on said frame, a conveyor adapted to be detachably mounted adjacent to any one of said outlets and means for driving said conveyor from said motor when 25 mounted adjacent to each of said outlets.
5. The combination with an auto truck and its motor, said truck having a body provided with a discharge opening, means driven by motor for tipping the body to direct material therein toward said discharge opening, driving mechanism on the truck adapted to be operated by said motor and comprising a shaft located adjacent to said opening, a conveyor adapted to be detachably engaged with the truck to receive the truck load discharged through said opening, and means for connecting said conveyor with said shaft to operate the conveyor from the truck motor and deliver the load as it is received from the body to a distant point.
- 30 35 40 6. The combination with an auto truck and its motor, said truck having a body provided with a discharge opening, means driven by motor for tipping the body to direct material therein toward said discharge opening, driving mechanism on the truck adapted to be operated by said motor and comprising a shaft located adjacent to said opening, a conveyor adapted to be detachably engaged with the truck and comprising an endless belt, a driving roller for operating said belt, and means for detachably connecting said driving roller with said shaft to operate said belt from the truck motor
- 45 50 and deliver the load as it is discharged through said opening to a distant point.
7. The combination with an auto truck and its motor, said truck having a body provided with a discharge opening in its rear end, means driven by motor for tipping the body to direct material therein toward said discharge opening, driving mechanism on the truck adapted to be operated by said motor and comprising a transverse shaft located adjacent the discharge opening in the body, a conveyor adapted to be detachably engaged to the truck adjacent said opening and said transverse shaft, and detachable means for connecting the conveyor to said transverse shaft whereby the conveyor is driven from the truck motor.
8. The combination with an auto truck and its motor, said truck having a body provided with a discharge opening in its side, driving mechanism adapted to be operated by said motor and comprising a longitudinally extending shaft mounted on the truck adjacent said side opening, a conveyor adapted to be detachably engaged to the truck adjacent said side opening and said shaft, and detachable means for connecting the conveyor to said shaft whereby the conveyor is driven from the truck motor.
9. The combination with an auto truck and its motor, said truck having a body provided with a discharge opening in its side and adjacent its rear end, a chute on the truck adjacent said opening and comprising a bottom angularly disposed to a horizontal plane, means for tilting the body so that said bottom will be substantially horizontal, a conveyor adapted to be detachably engaged with the truck adjacent said chute, and means operated by the truck motor for driving said conveyor.
- 95 10. The combination with an auto truck and its motor, of an operating shaft extending longitudinally of the truck and adapted to be driven by the truck motor, a transverse shaft supported on the truck at the rear end thereof, a side shaft supported on the truck adjacent the rear end thereof and geared to said transverse shaft, and means for driving said side shaft from said operating shaft.

HENRY BARKMANN.
ALOIS KUTSCHA.
